UNITED STATES PATENT OFFICE

104,005

DESIGN FOR A SHOE

Burton L. Wales, Abington, Mass., assignor to
The Stetson Shoe Company, Inc., Weymouth,
Mass., a corporation of Massachusetts

Application February 18, 1937, Serial No. 67,723

Term of patent 7 years

To all whom it may concern:

Be it known that I, Burton L. Wales, a citizen of the United States of America, residing at Abington, in the county of Plymouth, Commonwealth of Massachusetts, have invented a new, original, and ornamental Design for a Shoe, of which the following is a specification, reference being had to the accompanying drawing, forming part thereof.

In the drawing:

Fig. 1 is a plan view of a shoe, showing my new design, and

Fig. 2 is a side elevation.

I claim:

The ornamental design for a shoe, substantially as shown.

BURTON L. WALES.
